UNITED STATES PATENT OFFICE.

WILLIAM C. PEET, OF NEW YORK, N. Y., ASSIGNOR TO THE J. L. MOTT IRON WORKS, OF NEW YORK, N. Y., A CORPORATION OF NEW YORK.

DESIGN FOR A LAVATORY.

SPECIFICATION forming part of Design No. 36,595, dated October 20, 1903.

Application filed August 15, 1903. Serial No. 169,598. Term of patent 7 years.

To all whom it may concern:

Be it known that I, WILLIAM C. PEET, a citizen of the United States, residing at New York city, borough of Manhattan, in the county and State of New York, have invented a new, original, and ornamental Design for a Lavatory, of which the following is a specification, reference being had to the accompanying drawings, forming part thereof.

Figure 1 is a perspective view, and Fig. 2 is a plan view, of a lavatory, showing my new design.

What I claim as new, and desire to secure by Letters Patent, is—

The ornamental design for a lavatory as herein shown.

In testimony whereof I have signed my name to this specification in the presence of two subscribing witnesses.

WILLIAM C. PEET.
